INVALID LIFTS

Henry L. Dalton, Pico Rivera, Calif., assignor to Invalid Walker & Wheel Chair Co., Long Beach, Calif., a corporation of California

Filed Nov. 6, 1961, Ser. No. 150,248
3 Claims. (Cl. 4—185)

The present invention relates to invalid lifts, but more particularly to such devices which are connectible to bath tubs or other hygienic fixtures of a dwelling.

It has been common practice to employ lift apparatus of one kind or another for transporting an invalid patient from one location to another. Such devices have generally comprised a special form of chair or support means connected to a hoist mechanism. The invalid patient is seated in the chair and is then lifted from the bed or other location. Such devices have generally been provided with wheels whereby the entire lift device is easily moved across a surface as for instance the floor of a dwelling.

Frequently, such lift devices have been employed for transporting a patient to a bath tub or like apparatus. To position the patient in the bath tub, the lift device is rolled across the floor of the dwelling to the side of the tub. There, the seat of the lift mechanism is positioned adjacent to or over the bath tub, the patient then being lowered by the lift mechanism into the tub.

Such operations, however, have sometimes been difficult to accomplish due to several factors. Firstly, since the entire lift device is mounted on wheels or casters any sidewise force applied to the device has caused it to move away from the position adjacent the tub. Also, it is most desirable to employ cantilever type lift mechanism on such devices, and when they are rotated about a vertical axis in order to position the patient over the tub, the center of gravity of the lift device is outside the base thereby creating a tendency to tip. Needless to say, these or any other shortcomings are quite severe due to the nature of the act being performed.

In view of the foregoing it is an object of the present invention to provide an invalid lift which can be firmly anchored to the side of a bath tub or other hygienic fixture.

Another object of this invention is to provide an invalid lift which can be so positioned relative to a bath tub that a cantilever type lift mechanism can be positioned over the tub without creating a tendency for tipping the entire device.

Another object of this invention is to provide a frame to be mounted on the side of a bath tub or the like, and which is adapted to firmly secure an invalid lift device relative thereto.

Another object of this invention is to provide connecting apparatus for use with an invalid lift and a frame for mounting on a bath tub, such connection apparatus affording quick attachment and detachment between said lift and frame as desired.

Another object is to provide connection means for operation between an invalid lift and a mounting frame therefor, said connection means being manually operable in a quick and easy manner.

Another object of this invention is to provide an invalid lift which is simple and inexpensive to manufacture and which is rugged and dependable in operation.

The novel features which I consider characteristic of my invention are set forth with particularity in the appended claims. The device itself, however, both as to its organization and mode of operation, together with additional objects and advantages thereof, will best be understood from the following description of specific embodiments when read in connection with the accompanying drawings, in which:

2

FIGURE 1 is a perspective view of an invalid lift according to the present invention shown in operating position;

FIGURE 2 is a fragmentary elevational view of the connection means between the lift device and the mounting frame therefor;

FIGURE 3 is a fragmentary elevational view of the pneumatic operating means for the invalid lift;

FIGURE 4 is a sectional view taken substantially along line 4—4 of FIGURE 3;

FIGURE 5 is a fragmentary sectional view taken substantially along line 5—5 of FIGURE 1;

FIGURE 6 is a fragmentary sectional top view of the connection means shown in FIGURE 2; and

FIGURE 7 is a fragmentary sectional view taken substantially along line 7—7 of FIGURE 6 of the drawings.

Like reference characters indicate corresponding parts throughout the several views of the drawings.

Referring to FIGURE 1 of the drawings, the embodiment chosen for illustration of the present invention comprises a lift device designated generally by the numeral 10 and a mounting frame identified by the numeral 12.

Lift device 10 comprises a base 14 which includes a pair of relatively movable tubular leg members 16 and 18 mounted on wheels or casters 20. As will be readily appreciated by those persons skilled in the art, such casters are provided with suitable bearings for frictionless movement of the entire device as will hereinafter appear in greater detail, said casters also being so constructed as to swivel about the connection thereof to the tubular members. Such construction, of course, greatly facilitates the ease of transporting the lift device across a given surface as will hereinafter become more apparent. The wheels employed in the casters 20 may be made of plastic, rubber or any other suitable material.

As shown most clearly in FIGURES 2 and 6 of the drawings, each tubular leg member 16 and 18 is connected at one end to a vertically disposed small section of tubing as shown at 22 and 24, respectively. Such

sections of pipe are movably mounted between a pair of connecting plates 26 and 28. An operating lever 30 having a handle portion 30a is mounted on upper connecting plate 26 for co-action with tubular leg members 16 and 18. Operating lever 30 may be connected to any desired mechanism for angularly moving tubular legs 16 and 18 inwardly and outwardly as desired. A typical structure for accomplishing such movement comprises a cam member (not shown) attached to operating lever 30 and cooperable with a pair of actuating lugs (also not shown) operatively associated with leg members 16 and 18.

For holding connection plates 26 and 28 in predetermined spaced relation as shown in FIGURE 2 of the drawings, there is provided a tubular member 32 to which such connecting plates may be attached as by welding, soldering, brazing or the like.

Within tubular member 32 is positioned a lift mechanism identified generally with numeral 34 and comprising a vertical support 36 in the form of a hollow tubular member which telescopically fits within tubular member 32. To support this mechanism 34 within tubular member 32, there is provided a retaining plug 38 which is rotatably mounted by bearing means 40 within the lower end portion of tubular member 32. Plug 38 is attached to the inner race of bearing 40 for rotation within tubular member 32 as the lift mechanism 34 is pivoted about a vertical axis, the latter operation to be hereinafter described in greater detail.

The lowermost end of tube 36 is provided with a notch or opening 36a for alignment with an opening 32a in the lower portion of tubular member 32 and hence locking engagement with foot operated lever 42. Lever 42

is provided with an inwardly bent finger 42a which is urged into engagement with openings 32a and 36a by a compression spring 44.

Mounted on either side of shaft 36 are support handles 46 and 48 affording means for moving the entire lift device 10 as will hereinafter become more readily apparent.

Pivotedly attached to the top of support member 36 as by a pivot pin 50, is a cantilever arm 52 carrying a chair or support means identified generally with the numeral 54. A hydraulic lift mechanism 56 is interposed between lever 52 and support member 36, and comprises a tubular member 58 the lower end of which is attached to support member 36 and a rod 60 which telescopically fits within tubular member 58 and has an upper end pivotally connected to a bracket 52a on cantilever arm 52.

As shown most clearly in FIGURE 3 of the drawings, the lowermost end of tubular member 58 is provided with a ball 58a which is insertable within a socket 62a of a bracket 62, the latter of which is secured to support member 36 by welding, brazing or the like. A retaining cap 64 is threadedly mounted on bracket 62 for retaining ball 58a within the depression or socket 62a of bracket 62.

Attached to the side of tubular member 58 as by brackets 66 and 68, is a pneumatic unit 70 having a cylinder member 72 wherein is operatively positioned a piston (not shown) which is attached relative to an actuating lever 74. Lever 74 is pivotally mounted relative to cylinder 72 and carries a handle 74a for manual operation of the lift mechanism 34 as will hereinafter become more apparent. Pneumatic tubing 76 interconnects cylinder 72 with the lowermost portion of tubular member 58, there being suitable finger-operated valve means 78 for lowering the lift mechanism in accordance with well accepted practice.

Chair 54 is connected to one end of cantilever arm 52 by means of a Y-shaped hanger 30 having opposite end portions supporting chains 82 and 84. Suitable support means 86 and backrest means 88 are attached to chain members 82 and 84 to provide a chair-like structure for supporting an invalid patient. As will be readily apparent to those persons skilled in the art, the particular construction of support means 54 is not critical with regard to the spirit and scope of the present invention, it being fully realized that substantially any kind of support means may be employed.

Mounting frame 12 is formed with substantially U-shaped members 90, 92, 94 and 96. Members 90 and 92 are connected together as by welding or the like to provide an end member for frame 12, whereas U-shaped members 94 and 96 are similarly attached to each other to provide the opposite end member thereof. Horizontal braces 98 and 100 are connected to U-shaped members 92 and 94 to provide a rigid mounting frame for straddling the side of a bath tub or other hygienic fixture within a dwelling.

Mounting means in the form of screws 102 are provided in threaded engagement with U-shaped members 90 and 96, as shown, for cooperation with the side of the bath tub. Each of such mounting screws is provided with an enlarged head having a knurled periphery to facilitate manual operation. As will be readily understood by those persons skilled in the art, such mounting screws may be provided with resilient pressure pads as at 104 to prevent scratching or marring of the side of the bath tub. In like manner, the portion of U-shaped members 90, 92, 94 and 96 which extend within the bath tub may be provided with pressure pads to prevent marring the surface of the bath tub.

Rigidly secured to U-shaped members 90 and 92 of mounting frame 12 is a connecting bracket consisting of a vertically disposed square rod or shaft 106 and a pair of transverse end members 108 and 110 attached to the opposite ends of shaft 106. Members 108 and 110

are secured to U-shaped members 90 and 92 by suitable bolts 112 as shown in the drawings.

A complementally shaped sleeve 114 is telescopically fitted over square shaft 106, there being fastening screws 116 threadedly positioned within the side wall of sleeve 114 for engagement with shaft 106 for adjustably positioning the connection bracket as will hereinafter appear. A tubular member 118 is carried by sleeve 114, the connection therebetween being made in any desired manner as by welding, brazing or the like. Tubular member 118 is of such length as to loosely fit between connection plates 26 and 28 of lift device 10 as shown in FIGURE 2 of the drawings. Plates 26 and 28 are formed with aligned openings. These openings can be simultaneously aligned with tubular member 118 when the lift device 10 is suitably positioned with respect to mounting frame 12. When this is accomplished, a locking pin 120 is positioned as shown in FIGURES 2 and 6 for retaining connection plates 26 and 28 in assembled relative position with respect to tubular member 118. Locking pin 120 is provided with a manual handle 120a and suitable stop means as at 120b, the latter being engageable with the topmost surface of plate 26 when pin 120 is dropped into locking position as shown in solid lines in FIGURE 2 of the drawings. In this regard, the broken line in FIGURE 2 showing locking pin 120 indicates a partially removed position.

The operation of the subject invalid lift is as follows.

Lift device 10, due to casters 20 on base 10, can be easily pushed across the floor of a building by an attendant. Due to the cantilever construction of lift mechanism 34, the base 14 of device 10 can be positioned beneath a bed or the like so that the chair or supporting means 54 of the lifting device is positioned immediately adjacent the patient.

By suitable adjustment of finger screw 78, the bleed valve (not shown) of the lift mechanism can be operated so as to cause the chair or support means 54 to be lowered. After the patient has been positioned on the support means, the actuating lever 74 can be manipulated as a pump handle thereby causing air to be forced through tubing 76 into the lower portion of cylindrical member 58. Such air pressure within cylindrical member 58 forces piston-like rod 60 upwardly thereby causing cantilever arm 52 to rotate upwardly about pivot pin 50. This action lifts the patient from the bed.

The entire lifting device 10 may then be pushed from the location of the bed to the bath tub or other hygienic fixture to be used by the patient. With the valve controlling screw 78 firmly positioned in flow preventing position, the cantilever lift mechanism will be retained in lifted position by the air pressure within cylindrical member 58. Also, as the lifting device is pushed through doorways or other restricted openings, the tubular base members 16 and 18 can be repositioned merely by actuation of operating lever 30. That is, in order to provide maximum support it is desirable to have tubular members 16 and 18 in widely separated relative positions to provide the widest possible base. However, upon approaching a doorway or the like, it may be necessary to manipulate actuating lever 30 such as to bring the pivotally mounted tubular members 16 and 18 toward each other.

While the patient is thus being transported from one location to another, the lift mechanism should be positioned such that the extension or finger 42a of lever 42 engages opening 36a of support member 36 to prevent rotation of the lift mechanism.

With mounting frame 12 previously attached to the side of the bath tub, as shown in FIGURE 1 of the drawings, if it is desired to place the patient in the tub, it is first necessary to attach the lifting device 10 to the frame. That is, device 10 can be moved along the floor or other surface until the connection plates 26 and 28 straddle tubular member 118 so that the openings in

plates 26 and 28 are aligned with the through central opening of tubular member 118. If such alignment is not readily accomplished, it is merely necessary to vary the position of tubular member 118 by loosening screws 116 so as to permit member 114 to move upwardly or downwardly with respect to square shaft 106. When member 118 is in the proper position, screws 116 may be tightened to retain the same in such position.

With the openings of connection plates 26 and 28 aligned with the opening of tubular member 118, it is merely necessary to drop locking pin 120 into its locking position as shown in the drawings. As a result, lift device 10 is firmly held in the proper position relative to the bath tub.

The patient on chair 54 can then be positioned over the tub merely by pivoting the entire lift mechanism about base 14. To accomplish this, it is first necessary to actuate foot operated lever 42 such as to retract end portion 42a thereof from within opening 36a of shaft 36. When this has been accomplished, the entire lift mechanism including chair 54 can be rotated on shaft 36, the latter rotating on bearing member 40. It is thus possible to position chair 54 over the bath tub so that suitable operation of the bleed valve controlled by screw 78 will effect lowering of the patient into the tub.

In order to remove the patient from the tub, the reverse operation is employed.

Throughout the aforescribed operation of lift device 10 in placing a patient in the tub or in removing him therefrom, the device 10 is firmly anchored to the side of the bath tub by means of mounting frame 12. Also, the present invention provides means for quickly and easily attaching the lift device to the mounting frame.

Although I have shown and described certain specific embodiments of my invention I am fully aware that many modifications thereof are possible.

I claim:

1. An invalid lift comprising, in combination, a movable base carrying a lift mechanism, a U-shaped mounting frame for straddling the side of a bath tub and including means for attaching said frame thereto, and means for connecting said base to said frame comprising a vertically disposed track on said frame and a tubular member adjustably mounted on said track, said connection means also including an apertured plate carried by said base for movement therewith to a position of alignment of the aperture in said plate with said tubular member, said connection means further including a locking

pin engageable with said plate and tubular member when in aligned relative position to thereby firmly fasten said base to said bath tub.

5 2. An invalid lift comprising in combination, a base formed of tubular members mounted on substantially frictionless wheels to enable said base to be moved on a surface, a lift mechanism mounted on said base for raising and lowering a patient, a generally U-shaped mounting frame for straddling the side of a bath tub and including finger operated fastening screws for attaching said frame thereto, and means for connecting said base to said frame comprising a vertically disposed tubular member adjustably fixed to said frame and a pair of spaced apertured connecting plates on said base for movement therewith into alignment with the opposite ends of said tubular member, said connecting means further including a locking pin insertable in the aligned tubular member and apertured plates, whereby said base can be firmly anchored to said frame during raising and lowering of the patient relative to said bath tub.

10 3. An invalid lift comprising in combination, a base formed of a pair of tubular members attached to a pair of connecting plates for relative movement and mounted on substantially frictionless wheels to enable said base to be moved on a surface, cam operating means on said connecting plates for adjusting the relative position of said tubular members, a cantilever lift mechanism mounted on one end of said base for raising and lowering a patient, a generally U-shaped mounting frame for straddling the side of a bath tub and including finger operated fastening screws for firmly attaching said frame thereto, and means for connecting said base to said frame comprising a tubular member fixed to said frame and a locking pin insertable therein, said connecting plates on said base being formed with aligned apertures for alignment with said tubular member for receiving said locking pin, whereby said lift mechanism is firmly anchored to said bath tub during raising and lowering of said patient.
